UNITED STATES PATENT OFFICE.

SOLOMON I. FISCHER AND MISCHEL KOROTTY, OF NEW YORK, N. Y.

RAZOR-BLADE-SHARPENING DEVICE.

1,201,712.

Specification of Letters Patent. Patented Oct. 17, 1916.

Application filed February 21, 1916. Serial No. 79,672.

To all whom it may concern:

Be it known that we, SOLOMON I. FISCHER and MISCHEL KOROTTY, citizens of the United States, residing at New York, in the county of New York and State of New York, have invented certain new and useful Improvements in Razor-Blade-Sharpener Devices; and we do declare the following to be a full, clear, and exact description of the invention, such as will enable others skilled in the art to which it appertains to make and use the same.

This invention relates to certain new and useful improvements in razor blade sharpening devices, and more particularly to an improved holder for securing safety razor blades in such position that they may be readily stropped.

A further object is to provide a pair of clamping members which when moved longitudinally relative to each other, will firmly clamp the blade therebetween, so that both edges of the blade will project beyond the same and in position to be sharpened.

A further object of the invention is to provide a device of this character which will be simple, strong, durable and inexpensive to manufacture, efficient and reliable in operation, and well adapted to the purpose for which it is designed.

With these and other objects in view, the invention consists of certain novel features of construction and combinations and arrangement of parts as will be more fully hereinafter described and pointed out in the appended claims.

In the accompanying drawings in which similar reference characters designate like parts throughout the several views:—Fig. 1 is a top plan view of a device constructed in accordance with this invention; Fig. 2 is a central longitudinal sectional view through the same taken on the plane of the line 2—2 of Fig. 1; Fig. 3 is a transverse sectional view taken on the plane of the line 3—3 of Fig. 2; Figs. 4 and 5 are perspective views of the two parts of the device; and Fig. 6 is a transverse section taken on the plane of the line 6—6 of Fig. 2.

Referring more particularly to the drawings, the numerals 1 and 2 represent a pair of clamping members between which the safety razor blade is to be clamped in the manner hereinabove to be described. Extending longitudinally from one of the ends of the clamping members 1 and 2 are handle

sections 3 and 4. The clamping members and end sections are, as clearly shown in the drawings, bowed transversely outwardly, and are made from two strips of metal, the side edges of the handle sections 3 and 4 being curved inwardly to a greater extent than the side edges of the clamping members 1 and 2, to contact with each other to form a substantially oval-shaped handle.

Secured to the clamping member 2 in any suitable manner, but preferably by soldering, are longitudinally aligned eyes in the form of inwardly bowed straps 5, the intermediate portions of which are substantially semi-circular in shape. Secured in a similar manner to the clamping member 1, are L-shaped lugs 6, the side edges of which converge toward their free ends to provide hooks for engagement with the straps 5. The free end of the clamping member 2 is provided with a plate 7 against which abuts the free end of the clamping member 1 when the latter is in its proper relative position, whereby to limit the longitudinal movement of the same.

The free ends of the handle sections 3 and 4 are provided with substantially oval-shaped plates 8 and 9, the plate 9 being provided with a rectangular aperture 10 near its upper edge for engagement with a lug 11, the latter extending inwardly from the inner face of the plate 8.

In use, a safety razor blade 12 is placed on the clamping member 2, the eyes 5 being extended through the apertures or slots 13 of said blade, as clearly shown in Fig. 2 of the drawings. The clamping member 1 is then applied, it being placed over the blade 12 and moved longitudinally relative to the clamping member 2, the aforementioned hooks 6 extending through the eyes 5, and the lug 11 extending through the aperture 10. Owing to the fact that the side edges of the hooks are converged toward their free ends and the intermediate portions of the eyes are substantially semi-circular in configuration, as the clamping member 1 is moved longitudinally relative to the clamping member 2, these two members will be forced tightly together, thereby firmly clamping the razor blade 12 between the same, as will be readily understood without further description.

From the foregoing, it may be readily seen that the objects of the invention have been effectively carried out. It is to be noted

that the razor blade may be easily and quickly placed in the holder or removed therefrom, and owing to the fact that there are no projecting parts, the razor strop 5 will not be injured while stropping the same. The construction is such that it may be used as a holder for a blade while shaving, unless it is desired to use the blade in connection with a safety razor, for which it was intended.

As various changes in form and proportion may be resorted to without departing from the spirit of this invention, we do not wish to be limited to the construction herein 15 shown and described other than that set forth in the appended claims.

We claim:

1. A blade holding device of the character described comprising a pair of transversely 20 curved rectangular strips of metal having one of their ends shaped to form clamping members, the other ends of said strips comprising handle sections, the side edges of said sections being curved inwardly to a greater extent than the side edges of said members to contact with each other to form 25 an oval shaped handle, longitudinally alined eyes secured to the inner side of one of said strips, hooks secured to the inner side of the

other strip and adapted to be extended 30 through said eyes when said strips are moved longitudinally relative to each other, and a plate arranged at the free end of one of said members and adapted to abut the free end of the other member to limit the longitudinal 35 movement of the same.

2. A blade holding device of the character described comprising a pair of clamping members movable longitudinally relative to each other, longitudinally alined eyes secured to the inner side of one of said members, the intermediate portions of said eyes being substantially semi-circular in shape, and hooks secured to the inner side of the other member and extending through said 45 eyes, the side edges of said hooks converging toward their free ends and engaged with the semi-circular portion of said eyes, whereby to move said members toward each other as they are moved relatively longitudinally. 50

In testimony whereof we have hereunto set our hands in presence of two subscribing witnesses.

SOLOMON I. FISCHER.
MISCHEL KOROTTY.
